UNITED STATES PATENT OFFICE.

FREDERICK HYMANS, OF YONKERS, NEW YORK, ASSIGNOR TO OTIS ELEVATOR COMPANY, OF JERSEY CITY, NEW JERSEY, A CORPORATION OF NEW JERSEY.

ROPING FOR HOISTING APPARATUS.

Application filed September 12, 1924. Serial No. 737,300.

This invention relates to the roping employed in connection with hoisting apparatus of the type in which the weight of a load carrying device suspended from a drum or sheave is balanced at least partly by a counterweight.

The principle of this invention involves the provision of means for causing the travel of the counterweight to be less than the travel of the load carrying device, but in some proportion thereto.

The invention will be described, as applied to an elevator system, in connection with the accompanying drawing in which,—

Figure 1 is a schematic view of an elevator system employing chain compensation and embodying the invention,

Figure 2 is a schematic view of an embodiment of the invention as applied to an elevator system employing rope compensation.

Referring to the drawings, a cage 1 is shown suspended by rope 2 which passes over an upper grooved sheave 3, then downwardly around a sheave 4 and from sheave 4 to a hitch 5 secured in fixed position at the upper end of the hoistway. Sheave 4 is secured to shaft 6 which is rotatably mounted at the upper end of an extension 30 of the frame of counterweight 7. It will readily be seen that, as sheave 3 is rotated to raise or lower cage 1, counterweight 7 moves one-half as far as cage 1 and at one-half its speed. If it is desired to balance the weight of cage 1 exactly, the weight of counterweight 7 is made equal to twice the weight of cage 1. For example, assume that cage 1 is lowered from the position shown at the 4th floor to the 1st floor, counterweight 7 moves up half the distance between the 1st and 4th floors. Further assume that the cage moves at a speed of 800 feet per minute and that its weight is 3000 pounds. The weight of counterweight 7 required to balance the weight of cage 1 will then be 6000 pounds and the counterweight will travel at the rate of 400 feet per minute.

Calculating the kinetic energy we find—

Kinetic energy of cage=

$$50 \quad \frac{3000}{2 \times 32.16} \times \left(\frac{800}{60}\right)^2 = 8292 \text{ foot pounds}$$

Kinetic energy of counterweight=

$$55 \quad \frac{6000}{2 \times 32.16} \times \left(\frac{400}{60}\right)^2 = 4146 \text{ foot pounds}$$

Total kinetic energy of cage and counterweight=

$$8292 + 4146 = 12438 \text{ foot pounds.}$$

Comparing this with the well-known roping system in which the counterweight moves through the same distance and at the same rate as the cage a large reduction in the kinetic energy of the cage and counterweight is found. In the latter case, assuming the same weight and speed of cage, the counterweight required to balance the cage is 3000 pounds and its speed is 800 feet per minute. The kinetic energy is as follows:

Kinetic energy of the cage=

$$70 \quad \frac{3000}{2 \times 32.16} \times \left(\frac{800}{60}\right)^2 = 8292 \text{ foot pounds}$$

Kinetic energy of the counterweight=

$$75 \quad \frac{3000}{2 \times 32.16} \times \left(\frac{800}{60}\right)^2 = 8292 \text{ foot pounds}$$

Total kinetic energy of cage and counterweight=

$$8282 + 8292 = 16584 \text{ foot pounds.}$$

From the above it is seen that when using a roping according to the assumed example the reduction in kinetic energy of the cage and counterweight amounts to $16584 - 12438 = 4146$ foot pounds or 25 per cent. This reduction in kinetic energy has many advantages among which are a corresponding decrease in time of starting and stopping for the same torque on the hoisting sheave and less liability of slipping the ropes in starting and stopping with a given acceleration and retardation.

In Figure 1 a compensating chain 8 is shown as attached at one end to the cage and at the other end to a fixture 9 located near the center of travel of the cage. The weight of chain 8 is so selected that as the cage is raised and lowered, the change in weight of rope 2 (for which a plurality of ropes may obviously be substituted if desired) is compensated for by change in weight of chain 8, so that the weight suspended from sheave 3 on the cage side is constant at all points of travel for the same load in the cage. A second chain 10 hangs between counterweight 7 and a fixture 11 preferably located at a point one-quarter of the distance from the lower floor to the top floor, which location minimizes the length

of chain required, since the travel of the counterweight is one-half the travel of the cage. The weight of chain 10 is made such that it compensates for the change in weight of the portion of rope 2 on the counterweight side of sheave 3 so that the weight suspended on that side is at all times constant.

It is to be noted that in hoisting apparatus according to this invention it is necessary to install guide rails for the counterweight in the hoistway for a portion of its length only. Where the counterweight moves one-half the distance moved by the cage, as illustrated, the counterweight guide rails may be one-half as long as the guide rails for the cage and located in such portion of the hoistway as may be deemed best.

In Figure 2 a compensating rope 12 extends from cage 1 downwardly under a sheave 13 mounted on tension weight 14, thence upwardly over a sheave 15 mounted on the lower end of the frame of counterweight 7 and from there downwardly to a stationary hitch 16. The function of tension weight 14 is to maintain compensating rope 12 in its proper relation to cage 1 and counterweight 7 while at the same time taking up any slack that may occur due to stretching or wear of the various parts. Neglecting the slight changes in length of ropes 2 and 12 due to stretching, it will be observed that sheave 13 will not move up or down as the cage is raised and lowered, but that the portion of compensating rope 12 between cage 1 and sheave 13 increases and decreases in length by the same amount as the portion of rope 2 between cage 1 and sheave 3 decreases and increases in length. In the same way the changes in length of the portions of rope 2 between sheave 3 and sheave 4 and between sheave 4 and hitch 5 are compensated for by the changes in length of the portions of rope 12 between sheave 13 and sheave 15 and between sheave 15 and hitch 16 respectively. Therefore the total weight suspended from sheave 3 is at all times equally divided between its two sides, for a given load in the cage. Rope 2 and rope 12 are shown as single ropes but obviously either may be replaced by several ropes, it being necessary, if it is desired to effect full compensation, to have the weight of the hoisting ropes equal to the weight of the compensating ropes per unit length.

What is claimed is:—

1. Hoisting apparatus comprising a cage, a counterweight therefor, operating connections between cage and counterweight for effecting counterweight travel in unison with

cage travel and at reduced ratio with respect thereto, and flexible means associated with the cage and counterweight for compensating for the variation in the distribution of the weight of said operating connections 65 during the raising and lowering of the cage and counterweight.

2. Hoisting apparatus comprising a rope secured at one end to a fixed point, a cage suspended from the other end of said rope, 70 a driving sheave over which said rope extends from said cage, a counterweight having a sheave hung in a dependent loop of said rope between said driving sheave and said fixed point, and counterbalance roping associated with the cage and counterweight and shiftable to compensate for the change in the distribution of the weight of the supporting rope for the cage and counterweight during the travel thereof. 75

3. Hoisting apparatus comprising a cage, a counterweight therefor, roping connections for effecting counterweight movement at reduced ratio with respect to the raising and lowering of the cage, and means for compensating for the variation in the distribution 85 of the weight of the roping during the raising and lowering of the cage and counterweight.

4. Hoisting apparatus comprising the 90 combination with a cage, a counterweight, driving mechanism, roping supporting said cage and counterweight and comprising means for effecting movement of said counterweight in reduced ratio to cage movement; of a compensating rope the entire length of which is supported by said cage and counterweight, and means for transferring from the one to the other the support of a length of compensating rope equal to 95 the increase in length of the ropes supporting the one and the decrease in length of the ropes supporting the other, during cage travel. 100

5. In hoisting apparatus, the combination 105 with a cage, a driving sheave, a counterweight, a hoisting rope sheave on said counterweight, and a hoisting rope supporting the cage and extending continuously therefrom over said driving sheave and under 110 said counterweight sheave; of compensating means comprising a compensating rope sheave carried by said counterweight, a guide sheave, and a compensating rope extending continuously from the cage, under said guide 115 sheave and over said compensating rope sheave carried by the counterweight.

In testimony whereof, I have signed my name to this specification.

FREDERICK HYMANS.
